TABLE

Joseph E. Kienel, P.O. Box K, Acworth, Ga. 30101

Filed Apr. 23, 1971, Ser. No. 136,892

Term of patent 14 years

Int. Cl. D6—03

U.S. Cl. D6—177

FIG. 1 is an isometric view of the table of my instant design;

FIG. 2 is a side elevational view on a reduced scale of the table shown in FIG. 1;

FIG. 3 is an enlarged sectional view taken substantially along line 2—2 in FIG. 1; and

FIG. 4 is an enlarged sectional view taken substantially along line 4—4 in FIG. 2.

The other side and end of the table are substantially the same as that shown in FIGS. 1 and 2.

I claim:

The ornamental design for a table, substantially as shown and described.
